UNITED STATES PATENT OFFICE.

CHARLES HERMANN WAECHTER, OF NEW YORK, N. Y.

ATTACHMENT FOR BATHTUBS.

1,353,313.

Specification of Letters Patent. Patented Sept. 21, 1920.

Application filed March 3, 1920. Serial No. 362,900.

To all whom it may concern:

Be it known that I, CHARLES HERMANN WAECHTER, a citizen of the United States, and resident of New York, in the county of 5 New York and State of New York, have invented certain new and useful Improvements in Attachments for Bathtubs, of which the following is a specification.

My invention relates to attachments for 10 bathtubs, particularly to devices for permitting the raising of the water level in such tubs above the overflow discharge openings thereof.

In bathtubs of the types of construction 15 now prevailing the overflow discharge opening is such a small distance from the bottom of the tube that a person of normal proportions finds it usually difficult to immerse his knees and shoulders in the water, particularly if the tub is not of full length. I propose in this invention to provide a closure for the overflow opening so that the level of the water may be raised several inches beyond the said opening, thus rendering complete submersion of the body possible. I 20 propose, further, to associate with the said closure a means for permitting the flow of water through the discharge opening when the level of the water in the tub exceeds a predetermined distance above the said opening. This feature of the attachment prevents an overflow of the water and renders a continuous renewal of the water possible.

Certain other objects and features of the 25 invention will be apparent from the following description of one form of embodiment thereof illustrated in the accompanying drawing in which:

Figure 1 is a view showing in side elevation one form of apparatus embodying my invention in operative position on a bathtub, and

Fig. 2 is a view showing in front elevation one of the members of Fig. 1, and

Fig. 3 is a similar view of another member of Fig. 1.

Similar characters of reference designate similar parts in each of the several views.

The attachment of my invention is shown 50 in full lines in Fig. 1, applied for the purpose hereinbefore stated to a bathtub 1, which tub is shown in dot and dash lines, which tub is provided adjacent its upper edge with an overflow discharge opening 2 which com-

municates with a discharge pipe 3. The 55 usual pipe and valve fixtures 4 for the supply of hot and cold water are indicated in the drawing and comprise the pipe member 5 which extends vertically downward close 60 to the opening 2. The attachment of the present invention comprises a substantially cup-shaped or concave member 6 an elevation of which, looking to the left in Fig. 1, is shown in Fig. 2. The diameter of the face 65 of this member is larger than that of the opening 2, so that it covers the same completely. A washer 16 of rubber, felt, or other suitable material is partially embedded in the rim of the member 6, to render the 70 closure of the opening substantially watertight. A helical spring 7 has one end attached to the back of member 6 and the other end affixed to a plate 8 which is provided as shown in Figs. 2 and 3, with a semi-cylindrical strip 9.

This strip engages the pipe 5 when the attachment is placed into position and the spring 7 serves to press the member 6 firmly into engagement with the wall of the bathtub, thus retaining the attachment in place. A tube 12 extends vertically from member 6 and communicates therewith by a hole 14 in the concave wall of the cup. This tube 75 serves to permit the discharge of water into pipe 3 when the water level reaches the top of the tube. A cover 13, Fig. 2, is provided for the top of tube 12 so that an even higher water level may be attained, when desired, where the dimensions of the tub permit 80 thereof.

To facilitate the placing of the attachment into operative position and also the removal thereof, I provide flanges 15 on the member 85 8 and flanges 11 on member 6. These flanges are grasped by the thumb and index finger 95 of each hand so that the spring may be compressed as the attachment is placed into position or removed from the tub. The flanges 11 are preferably curved sufficiently to accommodate the index fingers between them 100 and the wall of the tub, to permit the attachment to be readily grasped when the same is in position.

The distance through which the water 105 level may be raised in the tub depends of course on the length of tube 12, when the same is used without the cover 13, and in the average case a distance of several inches

will be found sufficient to cover the knees and shoulders of the bather and thus avoid the chilling thereof which would otherwise ensue, particularly if the water is hot and 5 the air cold.

Although I have shown and described herein only one form and arrangement of apparatus embodying my invention, it is readily understood that various changes and 10 modifications may be made therein within the scope of the following claims, without departing from the spirit and scope of the invention.

What I claim is:

- 15 1. In a device for permitting the raising of the water level in a bathtub above the overflow discharge opening thereof, which comprises a substantially cup-shaped member for covering said opening, a washer associated therewith for rendering said covering substantially watertight, a tube extending upward from said member for permitting flow of water into said discharge pipe when the level thereof reaches the top of said 20 tube, a member for engaging the water inlet pipe of the tub, said member having a semi-cylindrical surface substantially conforming to the surface of said pipe, a coiled spring having its end attached to said above-mentioned members, and arranged to press the 25 same into their respective positions, and flanges on the said members whereby the said spring may be compressed and the said device placed into and out of operative position.
- 30 2. In a device for permitting the raising of the waterlevel in a bathtub above the overflow discharge opening thereof, a member for covering said opening, a helical 35 spring having one end secured to said member, and means associated with the other

end of said spring for engaging the water inlet pipe of said tub.

3. In a shield for the overflow opening of bathtubs, a substantially cup-shaped member 45 for covering said opening, a member for engaging the water inlet fixture of the tub, and resilient means for operatively associating said members.

4. In an overflow attachment for tubs, a member 50 for covering said opening, a member for engaging the water inlet fixture of the tub, a resilient device for urging said members away from each other, and flanges associated with said members whereby said 55 attachment may be grasped and placed into and out of operative position.

5. An attachment for the overflow opening of a bathtub, comprising a member for substantially covering said opening, a pipe 60 extending vertically therefrom, said pipe being arranged to permit the flow of water through said opening when the waterlevel exceeds a predetermined distance above the said opening, and a member associated with 65 said attachment for engaging the water inlet pipe of the tub to hold the said covering member in operative position.

6. In a device of the character described, a substantially cup-shaped covering member, 70 a pipe extending vertically therefrom, said pipe being arranged to permit the flow of water through said covering member, a member for engaging the water inlet fixture of the tub, and a helical spring, having its 75 ends associated with said members for retaining the same in operative position.

Signed at New York, in the county of New York and State of New York, this first day of March, A. D. 1920.

CHARLES HERMANN WAECHTER.
